UNITED STATES PATENT OFFICE

RICHARD BAUMGARTEN, OF ERFURT, AND WILLY HESSELMANN, OF BERLIN, GERMANY, ASSIGNORS TO THE FIRM AEG-DEUTSCHE WERKE AKTIENGESELLSCHAFT, OF ERFURT, GERMANY

BOOKKEEPING MACHINE

Application filed April 5, 1929, Serial No. 352,876, and in Germany June 20, 1928.

Our invention relates to typewriters and more especially to bookkeeping machines. In this type of machines a sheet of paper known as the audit sheet is permanently carried on the platen and the matter which is being typed on forms such as statements of account, etc. is copied on the audit sheet.

It is an object of our invention to overcome certain difficulties in connection with the insertion of the forms in such machines, particularly into the lower paper guide, and with the aligning of the forms with respect to the matter on the audit sheet.

To this end we provide two sets of pressure rolls above the platen and we also provide mechanism for causing these sets to alternately engage the platen so that the audit sheet is held on the platen by one of the sets when it has been released by the other set, 20 and vice versa, and is never free.

One of the sets is constituted by the usual rolls on the paper guide rod which are adapted to be displaced on the rod for holding audit sheets of various widths. The other 25 set is constituted by a plurality of resiliently supported rolls in a rail which is fulcrumed in the side walls of the paper carriage.

When it is desired to insert a form and the paper feed rolls below the platen have 30 been lifted, the audit sheet is firmly held on the platen by the rolls of the first set, (the rolls on the paper guide bar) so that the audit sheet cannot move on the platen notwithstanding its being released by the feed 35 rolls. After the first set has been brought to bear on the platen as described, the rail with the other set is rocked so as to lift the rolls of the second set from the platen in order to permit insertion of the form.

40 When the form has been inserted, the first set is lifted and the second set is applied and holds the form and the audit sheet on the platen.

In order to facilitate the aligning of the 45 forms with respect to the matter on the audit sheet, we so design the above mentioned rail on which the second set of rolls is carried, that in the position of the rail corresponding to the insertion of the form its lower edge 50 indicates the writing point, so that the forms

are readily aligned in vertical direction, adjustable stops being provided for aligning them laterally.

In order to align forms having perforations, such as cards, we provide a straight-edge in combination with pins adapted to enter the perforations in the forms. Any number of pins may be provided for forms of various widths. In the example, which will be described, three pins are shown, one 55 on either side, and a third in a central or intermediate position.

Preferably the pins are secured to springs to enable them to yield when forms are extracted, or positive means like a cam shaft 60 may be provided for withdrawing pins which would be in the way.

In the drawings affixed to this specification and forming part thereof a device embodying our invention is illustrated diagrammatically by way of example.

In the drawings

Fig. 1 is a plan view showing one end of a platen and its accessories in the position in which the second set of rolls is applied to 75 the platen,

Fig. 2 is a similar view showing the other end of the platen and its accessories in the position in which the first set of rolls is applied to the platen.

Fig. 3 is a section on the line 3—3 in Fig. 1,

Fig. 4 is a section on the line 4—4 in Fig. 2,

Figs. 5—8 illustrate the mechanism for aligning perforated forms as referred to above,

Fig. 5 being a cross section of the platen showing the sets of rolls in the same position as Fig. 4,

Fig. 6 being an elevation of the straight-edge supporting the pins viewed from the left 90 in Fig. 5, and

Figs. 7 and 8 being sections on the lines 7—7 and 8—8 in Fig. 6, respectively, drawn to a larger scale.

Referring now to the drawings and first 95 to Figs. 1 to 4, 10, 10 are the sides of the platen carriage which are connected at the rear by a stay 8, 1 is the platen, 1' and 1" are the usual knurled handles for rotating the platen, 2 is the usual lower paper guide 100

with the rocking feed rolls 3 and 4, 5 is the usual paper guide bar and 6, 6 are the rolls of the first set which are adapted to be displaced axially on the guide bar for the purpose mentioned. The guide bar is arranged to rock about the stay 8 by means of two arms 7, 7, 17, 17 are links fulcrumed on the ends of the bar 5 beyond the arms 7, 16, 16 are arms which are pivotally connected with the links 17 at 16', and 9 is a sectioned rail which is secured to one of the arms 16 at either end and is fulcrumed in the sides 10 by trunnions 9a. The rail comprises a straight lower part 9b and a curved upper part 9c. 11, 11 are curved plate springs which are secured to the base of the curved section 9c by rivets 11' (Fig. 1). The free ends of the springs are turned up and perforated to support trunnions at the ends of rolls 12 which constitute the second set. 13 is a bar extending in parallel to the lower straight section of the rail 9, and 14 is a stop which is adapted to be displaced on the bar for aligning the forms laterally. Any number of stops may be provided.

18 are pull-back springs each of which is attached to a pin 19 on one of the sides 10 at one end, and to a pin 20 on the rail 9 at the other end. 30 In operation with a form *b* inserted above the audit sheet *a*, the parts are in the position illustrated in Fig. 3, in which the paper guide rod 5 with the first set of rolls 6 is in its upper final position and the second set of rolls 12, exerts pressure on the form and the audit sheet. The springs 18 are under tension and hold the rolls 12 firmly applied onto the form and the sheet while the rolls 12 are applied to the form *b* under resilient pressure by their own plate springs 11.

When it is desired to insert a form as shown in Fig. 4, the paper guide rod 5 is depressed so as to bring the first set of rolls 6 to bear on the audit sheet *a* and to hold it on the platen notwithstanding its being released by the guide 2 and the feed rolls 3, 4. Simultaneously with the depression of the rod 5 and through the medium of the links and arms 16, 17, the rail 9 is rocked about its trunnions 9a so that the rolls 12 of the second set are lifted from the platen 1 and the lower edge of the straight rail section 9b is moved so as to indicate the proper position of the form *b* in vertical direction. In lateral direction the form is aligned by the stop or stops 14. In this position the springs 18 are also under tension and hold the bar 5 with the rolls 6, 6 firmly to the platen 1. The inner face of the straight section 9b serves 55 as a guide for the form *b* while it is being inserted.

Referring now to Figs. 5 to 8, 32, 32 are brackets on the paper guide bar 5 to which a straight-edge 31 is secured by screws 32' (Fig. 6). Secured to the rear of the straight-

edge 31 by rivets 36 are three U-shaped springs 35, 35' and 35'', one at each end and the third in a central position, but any other number of springs may be provided, if desired. Each spring is provided with a pin 37, 37' and 37'', respectively, which pins are adapted to project from the front face of the straight-edge 31 through perforations in the straight-edge so as to enter the corresponding perforations in the forms. The springs which tend to withdraw the pins from the perforations are under the control of a cam shaft 39 with a handle 40 at one end which is carried to rotate in the brackets 32, and is also adapted to be displaced axially in such bearings for a purpose which will presently be described.

The cam shaft 39 is provided with notches 38 in line with each spring. When the shaft is in such position that its solid portion engages one of the springs, its pin of the spring will be forced out of the perforation in the straight-edge as shown for the spring 35 and its pin 37 in Fig. 8. In addition to the notch 38 the cam shaft 39 is provided with a notch 31 at the central spring 35' which notch extends at right angles to the notch 38 as shown in Fig. 7. When the shaft 39 is in its normal position the three springs are controlled in unison by the notches 38 but when forms are inserted which extend throughout the width of the straight-edge and have no perforations for the central or intermediate pin 37', it is desirable that this pin should not protrude. In such cases the cam shaft 39 is displaced axially so as to place the notch 41 opposite the central spring 35'. As will appear from Fig. 6 the notches 38 are wider than the notch 41 so that they will remain in operative position with respect to their springs notwithstanding the axial displacement of the cam shaft 39. When the shaft 39 is now rotated anti-clockwise as viewed in Figs. 7 and 8, the notch 41 will prevent operation of the central spring 35' while the outer spring 35 and 35'' are operated as usually. On the other hand, with the cam shaft not displaced, all the springs are operated, i. e. alternately moved forward and released by the solid sections of the shaft and the notches 38.

We wish it to be understood that we do not desire to be limited to the exact details of construction shown and described for obvious modification will occur to a person skilled in the art.

In the claims affixed to this specification no selection of any particular modification of the invention is intended to the exclusion of other modifications thereof and the right to subsequently make claim to any modification not covered by these claims is expressly reserved.

We claim:

1. A bookkeeping machine comprising a

- carriage, a platen in said carriage, a pair of rocking arms fulcrumed on said carriage, a paper-guide bar secured to the free ends of said arms, a first set of rolls on said bar, a rail fitted to rock about a pair of trunnions in said carriage, a second set of rolls on said rail, and means connecting said paper-guide bar and said rail so as to alternately apply said first and second sets of rolls to said 5 platen as said arms are rocked. 70
2. A bookkeeping machine comprising a carriage, a platen in said carriage, a pair of rocking arms fulcrumed on said carriage, a paper-guide bar secured to the free ends of 15 said arms, a first set of rolls on said bar, a rail fitted to rock about a pair of trunnions in said carriage, a second set of rolls on said rail, means including a toggle-lever mechanism and connecting said paper-guide bar 20 and said rail so as to alternately apply said first and second sets of rolls to said platen as said arms are rocked. 75
3. A bookkeeping machine comprising a carriage, a platen in said carriage, a pair of 25 rocking arms fulcrumed on said carriage, a paper-guide bar secured to the free ends of said arms, a first set of rolls on said bar, a rail fitted to rock about a pair of trunnions in said carriage, plate springs on said rail, 30 a second set of rolls mounted to rotate in the free ends of said plate springs, and means connecting said paper-guide bar and said rail so as to alternately apply said first and second sets of rolls to said platen as said arms 35 are rocked. 80
4. A bookkeeping machine comprising a carriage, a platen in said carriage, a pair of rocking arms fulcrumed on said carriage, a paper-guide bar secured to the free ends of 40 said arms, a first set of rolls on said bar, a rail fitted to rock about a pair of trunnions in said carriage, resilient means so arranged with respect to said trunnions as to oppose the turning of said rail about its trunnions 45 in any position of said rail, a second set of rolls on said rail, and means connecting said paper-guide bar and said rail so as to alternately apply said first and second sets of rolls to said platen as said arms are rocked. 85
5. A bookkeeping machine comprising a carriage, a platen in said carriage, a pair of rocking arms fulcrumed on said carriage, a paper-guide bar secured to the free ends of said arms, a first set of rolls on said bar, a rail 50 fitted to rock about a pair of trunnions in said carriage, a second set of rolls on said rail, and means connecting said paper-guide bar and said rail so as to alternately apply said first and second sets of rolls to said 55 platen as said arms are rocked, said rail being so designed as to serve as a paper-guide in the position in which the rolls of its set are removed from said platen. 90
6. A bookkeeping machine comprising a carriage, a platen in said carriage, a pair of 60 rocking arms fulcrumed on said carriage, a paper-guide bar secured to the free ends of said arms, a first set of rolls on said bar, a rail fitted to rock about a pair of trunnions in said carriage, a second set of rolls on said rail, and means connecting said paper-guide bar and said rail so as to alternately apply said first and second sets of rolls to said platen as said arms are rocked. 95
7. A bookkeeping machine comprising a platen, two sets of rolls adapted to engage said platen, means for alternately applying one and the other set onto said platen, a support connected with said means, and means on said support for engaging perforations in the forms inserted in said machine. 100
8. A bookkeeping machine comprising a platen, two sets of rolls adapted to engage said platen, means for alternately applying one and the other set onto said platen, a support connected with said means, pins on said support adapted to engage perforations in the forms inserted in said machine, and means for advancing and retracting said pins 105 in unison. 105
9. A bookkeeping machine comprising a platen, two sets of rolls adapted to engage said platen, means for alternately applying one and the other set onto said platen, a support connected with said means, pins on said support adapted to engage perforations in the forms inserted in said machine, and means for selectively advancing and retracting said pins. 110
10. A bookkeeping machine comprising a platen, two sets of rolls adapted to engage said platen, means for alternately applying one and the other set onto said platen, a support connected with said means, means on said support for engaging perforations in the form inserted in said machine, and a cam shaft for controlling said engaging means. 115
11. A bookkeeping machine comprising a platen, two sets of rolls adapted to engage said platen, means for alternately applying one and the other set onto said platen, a support connected with said means, means on said support for engaging perforations in the form inserted in said machine, and a cam shaft having various cam faces adapted to control said engaging means, said cam shaft being adapted to be displaced axially with respect to said engaging means. 120
12. A bookkeeping machine comprising a platen, two sets of rolls adapted to engage said platen, means for alternately applying one and the other set onto said platen, a support connected with said means, springs on said support, a pin on each spring adapted to move in a perforation in said support, a cam shaft adapted to control said springs so as to displace said pin with respect to said 125 perforations, a shaft adapted to be rotated 130

and to be displaced axially with respect to said support, and cam faces on said shaft adapted to cooperate selectively with said springs upon displacement of said cam shaft.

⁵ In testimony whereof we affix our signatures.

RICHARD BAUMGARTEN.
